UNITED STATES PATENT OFFICE.

JOHAN GUSTAF VIKTOR LANG, OF LONDON, ENGLAND, ASSIGNOR OF ONE-HALF TO EDWARD HIBBERD JOHNSON, OF LONDON, ENGLAND.

REGULATION OF ELECTRIC MOTORS.

No. 811,415.

Specification of Letters Patent.

Patented Jan. 30, 1906.

Application filed June 28, 1904. Serial No. 214,512.

To all whom it may concern:

Be it known that I, JOHAN GUSTAF VIKTOR LANG, electrician, a subject of the King of Sweden and Norway, residing at 16th Soho Square, London, England, have invented certain new and useful Improvements Relating to the Regulation of Electric Motors, of which the following is a specification.

This invention relates to the regulation of electric motors, particularly those of the kind that are employed for propelling vehicles and that work on what is known as the "regenerative system," in which the motors act as such while propelling and accelerating the vehicle and act as dynamos for generating and returning electric energy to the source of supply while braking or retarding the vehicle. Electric motors working on the above-stated system were disclosed in a prior 20 United States Patent, No. 767,154, granted to me on the 9th day of August, 1904, and were characterized by the use of a series excitation when propelling and accelerating and of a compound excitation when braking 25 the vehicle and regenerating current, the change from the one to the other of these two conditions of the motors being effected by the angular movement of a cylinder termed a "field-change cylinder," which was 30 actuated from the controller-handle in moving in one or other direction with reference to any particular speed-notch to which said handle might for the time being be set. The effect of this angular movement of the 35 said field-change cylinder was to bring one or other of two series or groups of contacts thereon into proper relationship with respect to one or other of two series or groups of stationary contacts and to thus cause the afore- 40 said change in the series or compound condition of the motors. Now it will be obvious that with such an arrangement when the motorman shifts the controller-handle from any particular speed-notch to which it has been 45 previously set and turns it in the backward direction required to impart to the motors their braking or regenerative characteristic—i. e., their compound condition—the consequent retardation of the vehicle and reduc- 50 tion in speed of the motors will eventually exhaust their regenerative capability at the particular speed-notch occupied by the con-

troller-handle and that if the motorman from ignorance of the fact of such exhaustion or from any other cause should not continue 55 the backward movement of the controller-handle to bring it to a lower speed-notch the motors (while still in their compound condition) will resume their propelling function by receiving current from the main supply 60 instead of supplying current thereto, with the result that the motors will then be manifestly performing a very light duty, and therefore operating at a very low efficiency, whereas, if at the moment the regenerative exhaustion 65 took place the motorman had moved the controller-handle in the direction necessary for converting the motors into their series condition—i. e., in a forward direction—they would be operating at a fairly high efficiency 70 instead of at the very low efficiency mentioned above.

It is the chief object of the present invention to provide for the automatic movement of the field-change cylinder to cause it to 75 change the motors from their compound condition to their series condition whenever the said motors (while in their compound condition) are reaching the degree of regenerative exhaustion above stated, so that at such 80 times the change is effected independently of the motorman and by an automatic agency whose action is absolute and free from all uncertainty.

According to this invention and for the 85 purpose of accomplishing the aforesaid object the field-change cylinder is subject to the action of two forces tending to angularly displace it to a limited extent in opposite directions, the predominance of one or other of 90 these forces deciding the direction in which the cylinder will move, and accordingly the condition to which the motors will be changed—that is to say, whether they will be in their series or their compound condition. The 95 said two forces are preferably obtained by a device or contrivance which is partly mechanical and partly electrical, the mechanical part comprising a spring or a suspended weight and the electrical part comprising a 100 solenoid, an armature movable in a magnetic field, or an electric motor. The mechanical force is constant in its action, but the electrical force only operates at such times when

the mechanical force is to be overcome. Therefore normally the mechanical force predominates and keeps the cylinder in the position in which its contacts bring about the series condition of the motors. If, however, the electrical part of the contrivance is energized, as is the case when the controller-handle is turned in a backward direction, said electrical part of the contrivance will exert a force that will overcome the mechanical force, and thus turn the cylinder into the position in which its contacts bring about the compound or regenerative condition of the motors. The circuits of the electrical part of the contrivance are preferably such that the initial energization thereof is effected by current from the main electric supply, which if not at once followed by a current from the regenerative source, due to the compound condition to which the motors have been changed by the movement of the field-change cylinder, will permit the mechanical part of the contrivance to reassert itself and turn the cylinder back to its normal position, thereby bringing about the series condition of the motors. If, however, a regenerative current does at once follow the initial current, such regenerative current will operate to maintain the electrical part of the contrivance energized, and consequently keep the motors in their compound or regenerative condition. As soon as the regenerative current ceases, however, the electrical part of the contrivance will become inoperative, and the mechanical part of the contrivance will predominate again, thus turning the cylinder into the position for bringing about the series condition of the motors.

In order that the said invention may be clearly understood and readily carried into effect, the same will be described more fully with reference to the accompanying drawings, in which—

Figure 1 illustrates diagrammatically the application of the aforesaid contrivance to the field-change cylinder of a controller which for sake of simplicity is shown for use with a single double-wound motor working on the aforesaid regenerative system, the said motor having four field-coils, which are adapted to be connected in parallel relationship when the motor is propelling and accelerating the vehicle and in series relationship to serve as a shunt-winding when the motor is regenerating current and braking the vehicle, as set forth in my prior patent mentioned above, one of the said windings being used as a series winding in whichever condition the motor may be working. Fig. 2 is a plan, and Fig. 3 an elevation, of the aforesaid contrivances applied to the field-change cylinder. Fig. 4 is a plan, and Fig. 5 an elevation, of a contact device forming part of the controller cylinder. Figs. 6 and 7 represent diagram-

matically modified forms of the aforesaid contrivance. 65

A^x represents the main controller-cylinder contacts, and A' the stationary row of contacts with which said main cylinder-contacts coöperate. 70

A represents a contact with which the boss A^s and the handle of the main cylinder is provided, (see Figs. 4 and 5,) and $A^2 A^3$ are stationary contacts, with which it coöperates.

The aforesaid boss A^s has radial pins or 75 projections A^7 lying between stop-pins A^6 on the cylinder A^x ; so that the controller-handle is capable of a certain amount of free movement in either direction in order to bring about the engagement and disengagement of 80 the aforesaid contacts without affecting the movement of the main controller-cylinder, said handle being held in an intermediate position of its amplitude of free movement by means of spring-pressure. 85

B^x represents the field-change cylinder, and B' is the row of stationary contacts with which the field-change-cylinder contacts coöperate. The vertical line $b' b'$ represents the series position of the field-change cylinder, and the vertical line $b^2 b^2$ represents the compounding position of said cylinder. 90

$d' d^2$ represent the armature of the double-wound motor, and $e' e^2 e^3 e^4$ represent the field-coils, the part e of which is connected 95 with the main circuit at all times.

$f' f^2$ represent the field-regulating resistances, the former for the shunt or compound field and the latter for the series field. 100

g represents the starting resistance.

h is a shunt-coil for the circuit-breaker i .

B^2 is the device or contrivance for actuating the field-change cylinder B^x , said device or contrivance in the example illustrated comprising for its electrical part a solenoid provided with two coils b^3 and b^4 , the former of which is a shunt-coil and the latter a series coil. The mechanical part of the contrivance comprises in the example illustrated a crank-lever b^5 , connected with the field-change cylinder, and a spring b^6 , fixed at one end to a stationary point and at the other end to the extremity of said crank-lever. 105 110

In the position in which the parts are represented in Fig. 1 let it be assumed that the mechanical part of the contrivance is predominating and holding the field-change cylinder in the position in which the motor is in its series condition—i. e., with the contacts in the position b' relatively to the row of stationary contacts B' —and also let it be assumed that the controller-handle is at the first speed-notch of the controller. Then the current flows from the trolley through the coil i to the contact 5 of row B' , thence to contact 6 of said row to contact 3 of row A' , contact 4 of said row to armature d' , contact 6, contact 5, armature d^2 , contact 7, contact 115 120 125

8, thence to contact 13 of row B', where the current divides, one part going to earth through field-coil e and contacts 10 and 11 of row A' and the other part going to contacts 5 8, 9, 14, and 15 of row B' B', whence it flows through field-coils e' , e^2 , e^3 , and e^4 , respectively, to contacts 10, 11, 16, and 17, rejoining at contact 12 the first part of the current through e and following the same path there-
10 with to earth. If now the motorman desires to convert the motors into their compound or regenerative condition for braking the vehicle, he turns the controller-handle backward and in so doing he first brings the contact A 15 against the stationary contacts A³ without moving the main controller-cylinder, owing to the aforesaid free movement of the handle, thereby closing a circuit for the main current through the shunt-coil b³ of the electrical part 20 of the contrivance before any movement of the main cylinder occurs. The said electrical part of the contrivance thus becomes energized and overcomes the resistance of the spring b⁶ and turns the field-change cylinder 25 B^x angularly into a position in which the contact-row b² engages with the stationary row B', with the result that the motors are converted into their shunt or compound condition—that is to say, their braking condition.
30 At the instant the contacts of the said row b² of the field-change cylinder reach the stationary contacts B' a short circuit consisting of the two movable contacts corresponding to 5 and 6 of row B' of the main current-path 35 is broken, thereby compelling the generated current obtained from the motors in their shunt or compound condition to pass through the coil b⁴ of the solenoid, and thereafter the current through the coil b³ is broken as the 40 final position b² of the field-change cylinder is reached, and the solenoid then depends for a continuance of its energy upon the said generated current. The current then flows as follows: from the regenerating-motors d² d'
45 over contacts 4 and 3 of row A', through coil b⁴ of the solenoid B² (the short circuit at contact 5 and 6 of row B' being broken) to the circuit-breaker, where the current divides, part going through the coil i and part going 50 through the shunt-coil h to the trolley and returning through the earth connection over contacts 10 and 11 of row A' to contact 12 of row B', through the compound coil e to the contact 8 of row A' and the negative terminal 55 of the regenerating-motor. The field-current is shunted at contact 1 of row A' and passes to contact 7 of row B', contact 8, coil e', contact 10, contact 9, coil e², and contact 11. The current then flows to contact 14, 60 through coil e³, to contacts 16 and 15, coil e⁴, contact 17, and thence to contact 12, where it joins the main current. Obviously when the generated current diminishes to such an extent as to no longer supply the necessary

power for keeping the electrical part of the 65 contrivance energized the mechanical part becomes again predominant, and its spring b⁶ automatically returns the field-change cylinder to the position in which the motor is in the series condition. 70

It is necessary to provide for the contingency of requiring the propelling and accelerating function of the motor—i. e., its conversion into the series condition—while the regenerative current is still being supplied by 75 the motor, and therefore still keeping the electrical part of the contrivance active and the field-change cylinder in its compounding position. This contingency would arise if the motorman, having performed a rearward 80 movement of the controller-handle, as stated above, should turn the handle in a forward direction. For meeting this contingency the electrical part of the contrivance may be arranged in a circuit which enables it to be de- 85 energized by the main current being sent around the solenoid in an opposite direction to that which it previously flowed or by short-circuiting the said solenoid. In the drawings the latter provision is made, so that on the 90 forward movement of the controller-handle the contacts A² become engaged, and the then active coil b⁴ of the solenoid is short-circuited, thereby rendering said solenoid dormant and permitting the mechanical part of 95 the contrivance to become predominant, thus turning the field-change cylinder into the position for converting the motor into the series condition, as explained above.

It will of course be understood from the 100 foregoing description that after the controller-handle has been moved in either direction to bring about the engagement of the contacts A² or the contacts A³ the further continued movement of said handle will operate the 105 main controller-cylinder in the ordinary manner and bring about the necessary change of contacts for effecting the changes in speed of the motor. It has not been thought necessary to describe the various steps in the 110 movement of the main controller-cylinder and the alteration in circuits resulting therefrom in order to bring about the speed changes, as these operations are well understood. 115

A further advantage arising from the fact that on the failure of the motor to supply current during its regenerative working it automatically assumes its series condition is as follows: It is well known that if the connection between a regenerative motor equipment and the source of electric supply should be broken while the motors are in their regenerative or compound condition and that if the potential energy of a gradient or the continued backward movement of the controller-handle should cause an increase of the generating efficiency of the motor equipment to 120 125

take place the generated voltage due to the motors working as dynamos may rise to such an extent as to jeopardize the safety of the insulation of the motors. To prevent this occurrence, it has hitherto been usual to resort to special means, such as a shunt-field switch controlled by a small voltage-relay which by responding to a rise of voltage above the limit predetermined for it closes a circuit through the coil of the shunt-field switch and causes it to brake the shunt-field circuit. By the hereinabove-described contrivance this protection of the motors is afforded without the need of other or special devices, because in the event of connection with the source of supply being lost no regenerative current can pass to the line, and therefore none can pass through the winding b^4 of the solenoid with the result that the latter will no longer keep the field-change cylinder in its motor-compounding condition and the mechanical part of the contrivance will turn said cylinder into the position for converting the motor into the series condition. Another advantage afforded by the present invention is the reduction of the size and complication of the ordinary platform-controllers used on tramway-cars, in that only one of the aforesaid automatically-operative field-change cylinders is required for each car, which cylinder may be placed underneath the car in a suitable casing and be mechanically independent of the platform-controllers. The number of electric leads to the controllers are also greatly reduced, because the field-coils terminals need only be led to the single automatic field-change cylinder instead of, as heretofore, to two field-change cylinders, each of which constituted part of the platform-controllers. A still further advantage arises in the nature of an added factor of safety which results from the arrangement of the shunt h around the usual circuit-breaking coil i and the provision of the field-change cylinder with means for bringing it into use only when the equipment is performing its regenerating function, the contact 1 of the row B' completing the circuit through the shunt h . The motor can thus be called upon to perform a much higher duty with respect to retarding factors than is generally considered to be the proper limit of accelerating duty, because the shunt-path can be adjusted to increase the carrying capacity of the load-limiting switch to any desired extent. The function of the ordinary "overload-switch" is to protect the motor from damage by too great a current, the limit of the current being chosen accordingly. During the period that the motor is acting in its compound or regenerating condition for braking the vehicle another and more important consideration arises—viz., the avoidance of collision and danger to life of the passengers, and this is met by this invention by

the employment of an increased current limit 65 for the overload-switch.

Although the contrivance for oscillating the field-change cylinder has been herein described as being partly electrical and partly mechanical, which is preferable, it is possible to so arrange the said contrivance that it is wholly electrical in its action on the field-change cylinder by the employment of a relay, as represented in Fig. 2 of the drawings. In this case the crank b^5 of the field-change 75 cylinder is subject to the action of two solenoids b^7 b^8 , arranged on opposite sides thereof, with contacts b^9 b^{10} in the circuit of their windings. The tongue b^{11} of the relay is normally kept pressed against the contact 80 b^9 by a light spring b^{12} or a weight, whereby the main circuit will flow around the solenoid b^7 in the direction necessary for causing it to actuate the crank b^5 and turn the field-change cylinder into the position required 85 for the series condition of the motor. When, however, the controller-handle is turned in the backward direction, as aforesaid, to bring about the compound condition of the motor, the contact A , Fig. 1, engages the 90 contacts A^3 and closes the circuit through the shunt-coil b^3 of the electromagnet B, Fig. 2. The tongue b^{11} of the relay is thus attracted and caused to engage the contact b^{10} , thereby reversing the direction of the current and 95 causing the solenoid b^8 to become energized and the solenoid b^7 inoperative, thus reversing the position of the field-change cylinder, as in the previous case when the shunt-coil b^3 Fig. 1, was excited. Subsequently the 100 shunt-coil b^3 , Fig. 2, is thrown out of circuit, as before, and if the motor in its compound condition generates current of sufficient voltage the series coil b^4 of the electromagnet is 105 energized and maintains the tongue b^{11} in its shifted position in engagement with the contact b^{10} until such time as the regenerated current falls too low or the motor is changed back to the series condition, as already explained.

If desired, one of the aforesaid solenoids b^8 may be substituted by a spring b^{6x} , as shown in Fig. 3, in which case obviously only one of the contacts b^9 b^{10} would be required.

What I claim, and desire to secure by Letters Patent of the United States, is—

1. In regenerative motor-controlling means, the combination with the main controller-cylinder and the field-change cylinder, of means whereby the said field-change cylinder will automatically change the motor from its compound or shunt condition to its series condition, whenever the regenerated current of said motor, while in its compound or regenerative condition, falls below a predetermined value for the purpose specified.

2. In regenerative motor-controlling means, the combination with the main con-

troller-cylinder and the field-change cylinder, of means that tend to keep the field-change cylinder in the position for bringing about the series condition of the motor, means whereby the field-change cylinder is moved against the resistance of the first-mentioned means into the position for bringing about the compound or shunt condition of the motor, and means whereby the reduction in the regenerative current below a predetermined value permits the first-mentioned means to become dominant and to automatically return the field-change cylinder to its original position for the purpose specified.

3. In regenerative motor - controlling means, the combination with the main controller-cylinder and the field-change cylinder, of a magneto-electrical device, shunt and series windings thereon, means whereby the initial movement of the handle of the main controller-cylinder causes the shunt-winding to be momentarily energized and the field-change cylinder moved into the compound organizing position with relation to the motor, and means whereby the regenerative current energizes the series winding and maintains said cylinder in its shifted position

so long as said current does not fall below a predetermined value, substantially as and for the purposes described.

30

4. In regenerative motor - controlling means, the combination with the main controller-cylinder and the field-change cylinder, of a solenoid having shunt and series windings, circuits connecting said windings to fixed contacts at the main controller-cylinder, contacts on the handle of the main controller-cylinder coöperating with the fixed contacts for enabling the shunt-winding of the solenoid to become energized, contacts on the field-change cylinder coöperating with fixed contacts for enabling the series winding of the solenoid to become energized, and a spring tending to keep the field-change cylinder in its series organizing condition with relation to the motor substantially as and for the purpose specified.

In testimony whereof I have hereunto set my hand, in presence of two subscribing witnesses, this 17th day of June, 1904.

JOHAN GUSTAF VIKTOR LANG.
